HYDROCARBON OIL CONVERSION

Edwin F. Nelson, Chicago, Ill., assignor to
 Universal Oil Products Company, Chicago, Ill.,
 a corporation of South Dakota

Application May 9, 1928, Serial No. 276,264

8 Claims. (Cl. 196—58)

The present invention relates to improvements in process and apparatus for hydrocarbon oil conversion, and refers more particularly to a process and apparatus especially adapted to strip from 5 certain fractions, such as reflux condensate, desirable lighter ends which may be contained therein.

In hydrocarbon oil conversion processes it is proposed to employ a fractionating element to 10 separate the sufficiently converted fractions from the insufficiently converted fractions. Although many of these fractionating elements are highly efficient, few of them, if any, function perfectly, there generally always being a substantial quantity of the sufficiently converted fractions 15 entrapped with the insufficiently converted fractions which latter condense as reflux condensate.

It is an object, therefore, of the present invention to provide a process and apparatus especially 20 adapted to strip from the insufficiently converted fractions condensing as reflux condensate any of the sufficiently converted fractions which may be entrapped therein.

The process briefly described comprises with- 25 drawing from the system regulated quantities of the charging stock after it has been heated to a predetermined point and bringing it into direct and/or indirect contact with the reflux condensate in the fractionating element to heat and re-boil such reflux condensate to revaporize and strip 30 therefrom substantial amounts of the sufficiently converted fractions contained therein.

The advantages of this method of stripping the 35 reflux condensate will be readily apparent to those skilled in the art for it affords a simple, efficient and effective method of reboiling without the use of added equipment. Any of the conventional cracking apparatus may be easily altered to carry out the method with very little cost.

Other objects, features and advantages of the 40 present invention will be more apparent from the following detailed description.

The single figure in the drawing is a diagrammatic side elevational view, partly in vertical section, of apparatus in which the present invention 45 may be carried out.

Referring more in detail to the drawing, the raw oil or charging stock is drawn from a suitable 50 source through line 1 and forced by means of a pump 2 through the line 3 which communicates with the lines 4 and 5 controlled respectively by valves 6 and 7, whereby upon regulation of the latter any regulated portion of the charging 55 stock may be introduced into the dephlegmator 8

and/or any regulated portion of the charging stock may be introduced into the coil 9.

Assume for the purpose of illustration that all the charging stock is passed through the line 5 into the coil 9. The coil 9 may be mounted in a suitable furnace 10 provided with burners 11. While passing through the coil 9 the charging stock may be heated to a conversion and/or cracking temperature, flowing therefrom through transfer line 12, controlled by valve 13, discharging into the reaction and/or separating chamber 14 wherein the heated charges separate into vaporous and non-vaporous products of reaction, the latter comprising liquid and/or solids. The residue may be withdrawn from the chamber 14 through one or more of the draw-offs 15, controlled by valves 16. Manholes 17 may be provided at the top and bottom of the chamber. The vaporous fractions pass out of the chamber 14 through vapor line 18, controlled by valve 19, 20 and pass to the dephlegmator 8, wherein they undergo fractionation in the usual manner.

The vapors which remain uncondensed after passing through the dephlegmator 8 pass out therefrom through the line 20, controlled by 25 valve 21, thence through the condenser 22 and through line 23 controlled by valve 24. Condensed vapors and gases collect in the receiver 25 which is provided with gas relief line 26, controlled by valve 27, and with liquid draw-off 28, 30 controlled by valve 29.

Dephlegmation of the vapors may be assisted by introducing through the line 4 at the top of the dephlegmator 8, or at any other portion thereof, a regulated portion of the charging stock. The 35 reflux condensate formed, together with the un-vaporized portion of the charging stock, collects in the bottom of the dephlegmator and may be withdrawn therefrom through the line 30 controlled by valve 31, and directed by means of 40 pump 32 into the line 5 leading to the heating coil 9 as heretofore described.

As a feature of the present invention, one or 45 more lines 35, controlled by valves 36, may communicate with separate points of the heating coil 9. These lines 35 may be connected by means of a header 37 to the line 38, controlled by valve 39, which communicates with the lower portion of the dephlegmator 8, whereby regulated quantities 50 of the heated oil passing through heating tube 9 may be diverted and introduced into the dephlegmator and brought into direct or indirect contact with the reflux condensate therein. Since this heated oil is hotter than the reflux condensate 55

- the latter will be heated by the former whereby lighter desirable fractions will be boiled out from the reflux condensate, passing out through the line 20 as vapors, whereby they will be collected in the receiver 25. As the oil flows through the coil 9 its temperature is progressively increased, hence the temperature of the charging stock withdrawn from the coil 9 will vary according to the portion of the coil from which it is withdrawn.
- 10 By regulating at the same time the quantity of the charging stock withdrawn from the coil 9, a very close control over the heating of the reflux may be maintained. The charging stock so introduced into the dephlegmator 8 may be in 15 the liquid and/or vapor phase, depending on the point of the coil from which it is withdrawn and the conditions of operation.
- While I have shown the charging stock as being withdrawn intermediate the coil 9 it is to be understood that it may instead be withdrawn from the end thereof, or the transfer line 12. It is also to be understood that instead of introducing the heated charging stock into direct contact with the reflux condensate, the charging stock 25 may be passed through a closed coil which is submerged in the reflux condensate.
- 20 The particular conditions of operation are, of course, left to the judgment of a skilled operator. These conditions of temperature and pressure will 25 vary widely, depending upon the type of charging stock being used and the types of products desired. As an illustration, which is not to be construed in any way as a limitation of the invention, the oil passing through the heating coil 9 30 may be raised to a temperature of approximately 800 to 950° F., more or less, while being maintained under a superatmospheric pressure of from 25 to 200 lbs., more or less. Uniform pressure 35 may be maintained throughout the system or 40 differential pressures maintained on different parts of the system by obvious manipulation of the valve illustrated.
- I claim as my invention:
1. A hydrocarbon oil cracking process which 45 comprises passing the oil in a restricted stream through a heating coil wherein the oil is heated to cracking temperature, removing from the coil a portion of the oil passing therethrough and discharging the remainder thereof into a vapor separating zone, separately removing vapors and unvaporized oil from said zone and subjecting the former to dephlegmation to condense insufficiently cracked fractions thereof as reflux condensate, and re-boiling said reflux condensate by 50 admixing the same with said portion of the oil removed from said coil.
2. A hydrocarbon oil cracking process which 55 comprises passing the oil in a restricted stream through a heating coil wherein the oil is heated to cracking temperature, removing from the coil a portion of the oil passing therethrough and discharging the remainder thereof into a vapor separating zone, separately removing vapors and unvaporized oil from said zone and subjecting the former to dephlegmation to condense insufficiently cracked fractions thereof as reflux condensate, reboiling said reflux condensate by admixture with said portion of the oil removed from said coil, and returning to the coil the unvaporized 60 constituents of said portion of the oil.
3. A hydrocarbon oil cracking process which 65 comprises passing the oil in a restricted stream through a heating coil wherein the oil is heated to cracking temperature, removing from the coil a portion of the oil passing therethrough and discharging the remainder thereof into a vapor separating zone, separately removing vapors and unvaporized oil from said zone and subjecting the former to dephlegmation to condense insufficiently cracked fractions thereof as reflux condensate, reboiling said reflux condensate by admixture with said portion of the oil removed from said coil, and returning to the coil the unvaporized 70 constituents of said portion of the oil.
4. In a hydrocarbon oil cracking process of the character wherein the oil is heated to cracking temperature by passage through a heating coil and thence introduced into a vapor separating zone for separation into vapors and residue and the vapors dephlegmated to condense insufficiently cracked fractions thereof as reflux condensate, the improvement which comprises withdrawing from an intermediate point in the coil a portion of the oil passing therethrough while the remainder thereof is being directed through the rest of the coil and into said separating zone, and reboiling said reflux condensate by direct contact with said portion of the oil withdrawn from the 75 coil.
5. In a hydrocarbon oil cracking process of the character wherein the oil is heated to cracking temperature by passage through a heating coil and thence introduced into a vapor separating zone for separation into vapors and residue and the vapors dephlegmated to condense insufficiently cracked fractions thereof as reflux condensate, the improvement which comprises withdrawing from an intermediate point in the coil a portion of the oil passing therethrough while the remainder thereof is being directed through the rest of the coil and into said separating zone, and reboiling said reflux condensate by direct contact with said portion of the oil withdrawn from the coil, and returning the unvaporized portion of the resultant mixture to the coil for 80 retreatment in the process.
6. A hydrocarbon oil cracking process which comprises heating the oil to cracking temperature while flowing through a heating coil, removing the oil from the coil in two separate streams, discharging one of said streams into a vapor separating zone and effecting a separation of vapors from unvaporized oil therein, passing the vapors to a dephlegmating zone and condensing insufficiently cracked fractions therein as reflux condensate, and reboiling the reflux condensate in said dephlegmating zone by admixture with the other of said streams whereby the vapors evolved from the reflux condensate and from said other stream mingle with the vapors undergoing dephlegmation, and returning the unvaporized portion of the reflux condensate and the unvaporized portion of said other stream to the coil for further treatment in the process.
7. A hydrocarbon oil cracking process which comprises heating the oil to cracking temperature while flowing through a heating coil, removing the oil from the coil in two separate streams, discharging one of said streams into a vapor separating zone and effecting a separation of vapors from unvaporized oil therein, passing the vapors to a dephlegmating zone and condensing insufficiently cracked fractions therein as reflux condensate, and reboiling the reflux condensate in said dephlegmating zone by introducing the other of said streams into the lower portion of said dephlegmating zone to commingle with the reflux condensate therein whereby the vapors 90

evolved from the reflux condensate mingle with the vapors undergoing dephlegmation.

8. A hydrocarbon oil cracking process which comprises heating the oil to cracking temperature while flowing through a heating coil, removing a first stream of oil from the coil at a point intermediate the inlet and outlet thereof, removing the remainder of the oil as a second stream from the outlet of the coil and introducing the same to a vapor separating zone for sepa-

ration into vapors and unvaporized oil, passing the vapors to a dephlegmating zone and condensing insufficiently cracked fractions therein as reflux condensate, and reboiling the reflux condensate in said dephlegmating zone by direct contact with the oil of said first stream whereby the vapors evolved from the reflux condensate mingle with the vapors undergoing dephlegmation.

EDWIN F. NELSON. 10
